PAPER CLAMP

Walter C. Eickman, Dayton, Ohio, assignor to
 Harris-Seybold-Potter Company, Cleveland,
 Ohio, a corporation of Delaware

Application March 26, 1935, Serial No. 13,081
 Renewed January 30, 1939

21 Claims. (Cl. 164—54)

This invention relates to paper cutting machines, and particularly to mechanism for clamping piles of paper to the cutting table of paper cutting machines while they are being cut.

5 My clamping device is of the type that is self adjusting and operates automatically, clamping the paper with spring pressure before the knife reaches the paper in its descent and holding the paper until the knife has risen clear of it.

10 One of the objects of my invention is to compensate for variations in the tension of the spring due to differences in the thickness of the piles of paper, so that the clamping pressure imposed on the paper is practically uniform, regardless 15 of the thickness of the pile of paper. Another object is to perform the function of the mechanism with a comparatively short and light spring.

15 I have developed my invention in three forms, in the first of which there is but a single toggle joint, while in each of the other two forms there are a plurality of toggle joints.

In the accompanying drawings:

Figure 1 is a side elevation of the first form of machine, showing the parts in normal or inactive position;

Figure 2 is a rear elevation of the machine, with the parts in the position shown in Figure 1;

Figure 3 shows the operating mechanism of the machine at the end of half its cycle;

30 Figure 4 is a side elevation of the second form of my invention, in which a plurality of toggle joints cooperate;

Figure 5 is a rear elevation of the machine shown in Figure 4;

35 Figure 6 shows the position of the clamping mechanism shown in Figures 4 and 5 when the mechanism has moved one-half of its cycle and the machine contains a thick pile of paper;

40 Figure 7 shows a view similar to Figure 6, save that the pile of paper, not shown, is very thin;

Figure 8 is a rear elevational view of the third and preferred form of my invention, with the parts in their normal or home positions;

45 Figure 9 is a side elevational view of the structure shown in Figure 8, with the parts shown in their normal or home positions;

Figure 10 is a side elevational view of the structure shown in Figure 9, with the parts in the 50 positions they will occupy when a thin pile of paper is being cut, and

55 Figure 11 is a view similar to that shown in Figure 9, except that the parts are in the position they will occupy when a thick pile of paper is being cut.

In Figures 8 to 11 inclusive, the frame and some of the parts of the machine are omitted.

Referring now to Figures 1 and 2, the frame of the machine comprises a back 10, side frames 11, base 12 and a bed plate or table 13. An operating shaft 14 is mounted to rotate in bearings formed in the frame members 11, which shaft is rotated one revolution at a time by a gear wheel 15. The gear wheel 15 is rotated by a pinion 16, rigidly secured to a shaft 17, which shaft 17 is driven by a motor, not shown, through a clutch, also not shown, of the kind commonly used in driving paper cutting machines. A knife 18, mounted on a frame 19, is moved down and up in guides 20, by means of pitmans 21, only one of which is shown, operated by the crank 22 carried by the shaft 14. The clutch is so arranged that when the operator presses a small lever, not shown, the clutch is connected and made to rotate the shaft 14 one revolution, after which the clutch disconnects itself, leaving the shaft 14 in the position it occupies in Figure 1, that is, with the knife 18 elevated.

At 25 is shown a rock-shaft, at each end of which an arm 26 is rigidly secured. Above the table 13 a clamping member 27, mounted in suitable guides, is connected to the arms 26 by links 28. At 29 is shown a pile of paper in place on the table ready to be cut. See Figure 2. It is to be understood that this pile of paper may be 30 as high as can be conveniently placed under the clamping member 27, or it may be of any thickness less than that.

Rigidly secured to the rock-shaft 25, approximately 180° around from the arms 26, is an arm 35 30, to the end of which, at the point 31, is connected the strut 32 of a toggle joint. This strut is in reality a pair of links 32, one on each side of the arm 30. See Figures 2 and 3. For reasons of clearance, which will presently appear, 40 one of these links 32 (right-hand link shown in Figure 2) is made curved. A strut 33, the lower end of which is pivotally secured at 34 between lugs 34a formed on the base 12, is connected at 35 to the inner ends of the links 32, forming the 45 knee of the toggle joint. The term "toggle joint" as hereinafter used shall be interpreted in accordance with the following definition: "Two rods or plates, hinged together, and employed to transmit a varying force by lateral pressure on 50 the hinge, which is called the knuckle or knee". Pivotally connected to the inner end of the strut 33, near the knee 35, is the end of a threaded rod 36. This rod passes transversely and freely through a short shaft 37, which shaft is mounted 55

to rock in lugs formed on the back 10. Confined between this shaft 37 and a nut 38 screwed on the rod 36 is a compression spring 39. The nut is in fact a wheel with a threaded hub. The rod 5 36 might be connected directly to the knee 35, and in effect it is so connected, but in order to make the average position of the rod more nearly horizontal this separate connection is provided, as at 40. As will be readily seen, the spring 39 10 being a compression spring its tendency to expand in length tends to increase the distance between the shaft 37 and the nut 38, and thereby draws the connection 40 toward the shaft 37. In other words, the tension of the spring 39 tends 15 to straighten the knee of the toggle joint, thereby moving the rockshaft 25 clockwise, as it is seen in Figure 1, thus drawing the clamping member 27 down onto the pile of paper 29, and clamping the paper to the table 13. This very thing has 20 happened as the parts are shown in Figure 3. That is, the pivotal points 31, 34 and 35 of the toggle joint are more nearly in alignment in Figure 3 than in Figure 1, due to expansion of the spring 39.

25 As is well known, the power of a spring diminishes as its tension decreases. Therefore the power or tension of the spring 39 is less in Figure 3 than it is in Figure 1. As is also well known, the power required to produce a given endwise 30 pressure by means of a toggle joint becomes less and less as the struts of the toggle joint approach alignment with each other. It therefore follows that the decreasing power of the spring, as the clamping member 27 approaches the table, is 35 compensated for by the increasing leverage of the toggle joint, as the struts approach alignment. In fact, the loss in spring power can, if desired, be more than compensated for by the toggle because the ratio of pressure obtained 40 to the power expended increases as the struts approach alignment. It is not necessary to go into this, however. It suffices to say, which can be demonstrated mathematically if necessary, that by means of the toggle joint, a spring having 45 sufficient power to clamp the stack of paper with the parts in the position shown in Figure 1, can, by proper proportioning of the parts, be made to retain sufficient power to produce at least as much clamping pressure with the parts in the 50 position shown in Figure 3. Going a step farther it may be stated that the parts can be so designed that increased pressure is obtained when the pile of paper is high and reduced pressure when the pile is low, or the parts may be so 55 designed that the contrary result is obtained.

55 I have already stated that Figure 1 shows the parts in their normal or home position. Figure 3 shows the parts in the position they occupy at the end of the first half of a cycle, that is, with the shaft 14 turned 180° from the position it 60 occupies in Figure 1. An eccentric 45 is rigidly secured to the shaft 14, which eccentric carries a strap 46. Extending from the strap 46 is a slotted arm 47, which embraces a stud 48 that 65 projects laterally from the arm 30. Obviously, when the shaft 14, as shown in Figure 3, is rotated the remaining half of its cycle, that is to the position it occupies in Figure 1, the arm 47, through its connection with the stud 48, rocks 70 the shaft 25 to the position it occupies in Figure 1. This crooks the knee 35 and compresses the spring 39. It will be observed that in Figure 1 a line drawn from the center of the eccentric to the center of the stud 48 will pass through the 75 center of the shaft 14; in other words, the spring

is held by the eccentric being on a dead center. Thus no latch or similar mechanism is required to sustain the spring tension, which is at its maximum when the machine is in its normal position. When the machine is operated, the eccentric moves its full stroke at each revolution of the shaft 14. This permits the spring to move the clamping mechanism until the clamping member 27 becomes seated on the pile of paper that has previously been placed on the table. 10 Thus it is seen that the clamping mechanism is operated by the spring. The parts are so timed that the clamping member 27 seats itself on the pile of paper before the knife descends far enough to begin cutting the paper. On the second half of the cycle the knife rises above the paper before the end of the slot in the arm 47 reaches the stud 48, that is before the pressure of the clamping mechanism is removed from the pile of paper. Then the end of the slot in arm 47 engages the 15 stud 48, the remainder of the stroke of the eccentric is used in tensioning the spring and raising the clamping member 27 to the position it occupies in Figure 1. 20

25 I shall now describe the structure shown in Figures 4 to 7 inclusive. Referring principally to Figures 4 and 5, the frame of the machine comprises a front plate 50, side frames 51, a base 52 and a table or bed plate 53. An operating shaft 54 carries and is driven by a gear wheel 55. 30 A pinion 56 drives the gear 55 and a motor and clutch, not shown, drive the pinion. As before, the clutch is of the type commonly used on paper cutters. There is also a knife 58, mounted on a frame 59 in guides 60, moved down and up by 35 pitmans 61, only one of which pitmans is shown, operated by a crank 62 carried by the shaft 54, as before. A rock-shaft 65 carries arms 66 which are connected to a clamping member 67 by links 40 68, all as before.

One end of a strut of a toggle joint is attached to a lug 70 formed on the frame of the machine. This strut consists of two links 71, see Figure 5, which are connected to the lug 70 at 72. One end of the other strut 73 of the toggle is connected at 74 to the arm 75 of a lever of the first class, the fulcrum of which lever is pivotally connected at 76 between lugs 77 formed on the base of the frame. The struts 71 and 73 are joined at 78, the strut 73 being bifurcated to embrace the ends 50 of the links which constitute the strut 71. The joint 78 constitutes the knee of the toggle, and the rod that serves as the joint 78 passes transversely through the enlarged end of a guide rod 79. The guide rod 79 extends perpendicularly to 55 the toggle, and its outer end is adapted to slide in a bushing 80, which bushing in turn is screwed into an arm 81 extending upward from the base of the machine frame. Confined between the head 82 of this bushing and a flange 83 on the 60 other end of the rod, near the knee, is a compression spring 84, the tension of which spring tends to straighten the knee of the toggle. The tension of the spring is adjustable by screwing the bushing 80 one way or the other in the arm 65 81 and locking it with the jamb nut 85.

Rigidly secured to the shaft 54 is an eccentric 90, carrying an eccentric strap 91, having a wing 92 extending toward the left as seen in Figure 4. A pair of links 93 connect this wing 92 to the 70 end of an arm 94 that is rigidly secured to the rock-shaft 65, 180° around from the arms 66. A bifurcated link 95 embraces the wing 92 and links 93, its lower end being connected to the end of an arm 96. See Figure 5. This arm 96 is the 75

second arm of the lever of the first class, previously referred to, of which the first arm is 75, arranged to rock on the fixed fulcrum 76.

I shall now explain the operation of the machine just described beginning with the parts in the position they occupy in Figure 4, which is the normal or home position, the clamping member 67 being then at its highest point. It is held so by the spring 84, the spring being under a certain amount of tension, which I shall refer to as initial tension. This tension presses the knee 78 toward the right, which presses the joint 74 down on the pad 103, this in turn holding the lever 75-96 and the pivot 102 stationary. Rotating the shaft 54 one-half of a revolution, which is one-half of its cycle, will produce one of several conditions, according to how much paper may have been put under the clamping member 67. If a high pile of paper has been put under the clamping member 67, so that said member cannot descend far, the parts will ultimately assume a position somewhat like that illustrated in Figure 6. That is, referring again to Figure 4, the eccentric strap 91, including the wing 92 and pivot 100, will first move bodily to the left. As the pivot 102 is still held stationary by the initial tension of the spring 84, the link 95 will swing on the pivot 102 and the pivot 100 will move on the arc 104, see Figure 4. Meanwhile the upper end of link 93 will be rotating the shaft 65 through the pivot 101 and the arm 94, and through the arms 66 and links 68 (Figure 5) the shaft 65 will pull the clamping member 67 down on the pile of paper, thus arresting the movement of the pivot 100 along the arc 104. But with the bodily movement of the eccentric strap 91 still continuing to the left, the link 93 now begins to swing to the left on the pivot 101, which pivot has now become stationary, causing the pivot 100 to move to the left on the arc 105, Figure 6.

At this point begins an increase in the tension of spring 84, and it is done in this way: It will be noticed that the general direction of the arc 105, Figures 6 and 7, is slightly downward, and that continued bodily leftward movement of the eccentric 91 will cause the pivot 100 to move the link 95 downward. This will cause the link 95 to rock the bell-crank lever 75-96 counter-clockwise on its axis 76, thereby raising the joint 74 off of the pad 103. This puts more bend in the knee of toggle 71-73 and by moving knee 78 to the left, as seen in Figure 4, compresses the spring 84 further, thereby increasing the tension of the spring.

At first thought it would seem that this increase in the tension of spring 84 would increase the pressure of the clamping member 67 on the pile of paper, but remembering that as the bend in the knee 78 increases, the power of the toggle 71-73 or its mechanical advantage, so to speak, decreases, the increased power of the spring is practically offset by the decreased power of the toggle. At the same time an equalization is taking place between the toggle formed by struts 95 and 96 and the toggle 93-95. These equalizations are more or less complete according to the design of the toggles, and in any event the pressure of the clamping member on the pile of paper is maintained practically uniform, regardless of the thickness of the pile of paper under the member 67. This is illustrated in Figures 6 and 7, which will be further explained presently.

It will now be seen that in effect the clamping member 67 is positively moved down to the pile of paper by the shaft 54, up to the time the mem-

ber 67 comes to rest on the pile of paper; that is, only while the center 102 is held in a stationary position by the spring 84. In other words, it might as well be stationary in fact, up to the time the member 67 is stopped by the pile of paper. After this, however, the movement of the shaft 54 continuing, yielding of the spring 84 and counter-clockwise movement of the lever 75-96 is necessary to keep from breaking something. That is, the spring 84 serves two functions after the clamping member 67 comes to rest on the pile of paper: first, it acts as a relief to allow continued leftward movement of the eccentric 91, and second, it supplies the tension whereby the clamping member 67 holds the stack of paper while it is being cut.

To sum up the matter, the thickness of the pile of paper may vary from a very thin pile to a pile that taxes the capacity of the machine. But a spring tension of a given equal amount will answer the purpose in both cases, and in any intermediate case. It happens that a tension sufficient for holding the paper for cutting purposes is also sufficient for holding the center 102 stationary. Therefore, the initial tension of the spring 84 is obtained by compressing the spring with the threaded sleeve 83. As this tension is wholly expended in tending to straighten the toggle 71-73, which results in pressing the joint 74 to the pad 103, it does not require a very great movement of the sleeve 83. Therefore up to the time the clamping member 67 comes to rest on the pile of paper, the spring is comparatively little compressed. But, as the tension is augmented by the toggle 71-73, it follows that this comparatively small spring tension produces a considerable amount of pressure tending to hold the joint 74 to the pad 103, and holding the center 102 immovable. Referring to Figure 6, which it will be recalled depicts a case wherein a thick pile of paper has been placed on the table, resulting in the clamping member 67 having moved but a short distance, it will be seen that the spring 84 has been compressed a considerable amount, and compare this figure with Figure 7, where a thin pile of paper is under the clamping member 67, it will be seen how much less the spring becomes compressed when a thin pile is being operated upon. Comparing Figures 6 and 7 also shows that the equalization which is produced by the combination of toggles, as previously described, results in the pressure being substantially the same, whether a thick pile or a thin pile of paper is placed under the clamping member 67.

I shall now describe the third version of my invention; or rather what may best be described as a modified form of the double toggle mechanism just described. In this construction as in the other two, there are driving parts and connections, not shown, which operate a main shaft, in this case shaft 150, whereon is secured an eccentric 151, encircled by an eccentric strap 152, which strap is connected to the knee 153 of a toggle joint 154-155. The lower strut of this toggle comprises two links, 154-155, see Figure 8, the free ends of which are pivotally joined to an arm 156 which is keyed to a rock-shaft 157. The upper strut of the toggle comprises two links 153-155, the upper ends of which are pivotally connected to an arm 158, this arm being keyed to a rock-shaft 159. The rock-shaft 158 corresponds to rock shaft 65 of the structure shown in Figures 4 to 7.

The shaft 157 is mounted to rock in a pair of pillow blocks 160, these pillow blocks being

mounted upon the base of the machine. Keyed to this shaft are a pair of arms 161, which arms are in effect one arm and extend from the shaft in a direction substantially opposite to the direction in which the arm 166 extends. Between the free ends of the arms 161 a link 162 is pivotally attached at 162^a, which link forms one strut of another toggle joint. The other strut of this toggle consists of two links, 163, one on each side of the knee 164 of this last mentioned toggle joint. The upper ends of the links 163 are pivotally connected at 163^a to the outer end of an arm 165 which is mounted to rock freely on the shaft 158. Between the knee end of the strut 162 and the adjacent end of each strut 163 are the eyes of two threaded rods 166, the whole being united by a single pivot rod 164, which forms the knee of this toggle 162—163.

Each of the pillow blocks 160 has an upwardly, diagonally extending arm 167, each of which arms terminates in a notch or open bearing 168. Between the arms 167 is placed a U-shape frame, 169, the bottom of which is provided with two holes that slip freely over the tension rods 166. Each of the arms of this U-shape frame is provided with a trunnion 170, which trunnions rest in the bearings 168 and in which the frame 169 is adapted to rock. Compression springs 171 surrounding the tension rods 166 are confined between the nuts 172 and the bottom of the U-shape frame 169. The upper ends of the strut-links 163 are pivotally connected to an arm 165, which arm extends laterally from one end of a sleeve 175. This sleeve is arranged to rock freely on shaft 158. On the other end of the sleeve, extending laterally and substantially 180° from the arm 165, is another arm 176. Arms 165 and 176 are integral with the sleeve 175, and the three parts form in effect a lever adapted to rock on the shaft 158. Pivotally connected to the end of the arm 176 is one end of a link 177, the lower end of which link is pivotally connected to the joint 178. The joint 162^a, connecting the arms 161 to link 162, is adapted to rest on pads 179, formed on the base of the machine.

Keyed to the shaft 158, near each end, is an arm 180 (only one is shown), and pivotally connected to each of these arms is an upwardly extending link 181. These correspond to arms 26 and links 28, of Figures 1 and 2, which carry the clamping member 27 of these figures. These arms 180 and links 181 also correspond to arms 66 and links 68, respectively, of Figures 4 and 5. The clamping member, not shown, is adapted to clamp piles of paper of various thicknesses to a cutting table, also not shown, to be cut.

I shall now explain the operation of this structure, assuming that a pile of paper has been placed on the cutting table, and that mechanism for rotating the shaft 150 one revolution, which mechanism is not shown, has been started. I shall also assume that an initial tension has been imparted to the springs 171 with the nuts 172. Remembering that the springs 171 are confined between the bottom of the U-shape member 169 and the nuts 172, that the nuts are screwed on the tension rods 166, which rods are anchored in the knee rod 164, and that the trunnions 170 on the member 169 lie in the bearings 168, which bearings are immovable, it is plain that the spring tension is expended in pulling the knee 164 to the left as seen in Figure 9, and tending to straighten the toggle 162—163. This results in the joint 162^a resting on the pad 179, which in turn holds the pivot 178 stationary. All of this action is

similar to that of lever 75—96 and joint 102 of Figure 4. Rotation of the shaft 150 moves the eccentric strap 152 bodily to the left, as seen in Figure 9. The strut 154 swings to the left on the center 178, causing the strut 155 to rock the shaft 158 through the arm 159 and center 179, and as will be understood rocking of the shaft 158 will move the clamping member down to the pile of paper through the links 181 and the arms 180. When the clamping member comes to rest on the pile of paper, the eccentric strap continuing to move to the left, the shaft 157 will be rocked counter-clockwise by the strut 154 through center 178 and arm 156. All of this action is similar to that which has been described in connection with Figure 4.

From now on the springs 171 serve as a relief, to permit the continued bodily leftward movement of the eccentric strap 152, this being necessary because the clamping member is now resting on the pile of paper and as a consequence the center 178 has become immovable. Continued leftward movement of the eccentric strap now moves the arm 156 downward, with consequent counter-clockwise movement of the shaft 157. The arm 161 being keyed to shaft 157, it follows that as arm 156 moves downward, arm 161 moves upward. Simultaneously with downward movement of the arm 156, the link 177, which is connected by joint 178 to arm 156, is pulled downward, this in turn rocking the arms 176 and 165 counter-clockwise, the arm 165 in turn raising the strut 163. The arm 165 is preferably made a little shorter than the arm 176 because the pressure at 163^a should be greater than at 176^a in order to produce the proper final resultant pressure on the paper clamp through the links 181, etc. In this connection it will be understood that the amount of effective movement imparted to the pivot 162^a is greater than the amount of effective movement imparted to pivot 163^a, resulting in increased compression of springs 171, as I shall now explain.

The effective radial lengths of arms 176, 156 and 161 are substantially the same, while the effective radial length of arm 165 is less. This is due to the fact that an extended line 190, drawn through the centers of pivots 163^a and 164, crosses a line 191, radial to center 158, at a distance from center 158 shorter than the effective radial length of arms 176, 156 and 161. Therefore, when the center 162^a lifts strut 162, as a consequence of center 178 being pushed downward by strut 154, the strut 163 is prevented by the arm 165 from rising as great a distance as strut 162 tends to lift it. This is because the effective radial length of arm 165 is less than the effective radial length of arm 161. As struts 162 and 163 are connected by the knee 164, this excess movement of strut 162 results in increasing the bend in the knee of the toggle 162—163. The tension rods 166 being anchored in the knee 164, it is plain that increasing the bend in the knee 164 draws the rods 166 to the right as they are seen in Figures 9, 10 and 11, and since the springs 171 are confined between the nuts 172 and the U-shape frame 169, which frame is stationary, it is plain that increasing the bend in the knee 164 increases the compression in the springs.

Thus it is seen that this third version of my invention produces the same results that the second version produces. I shall now show that it produces an additional useful result, namely, means whereby the springs may be shorter, thereby taking up less room. It will be recalled that

after the clamping member comes to rest on a pile of paper, continued leftward movement of the eccentric strap produces compression of the spring in inverse proportion to the thickness of the pile of paper on which the clamping member is resting. It follows that in the structure of Figures 4 to 7, considerable compression of the spring takes place where a thin pile of paper is being acted upon, and it is obvious that the spring must be long enough to permit the necessary amount of spring compression which a very thin pile of paper will involve, without injury to the spring.

With the spring arrangement shown in Figures 8 to 11 the springs can be very short. This is because the amount of compression imparted to the springs can be varied by varying the effective radial length of arm 165 with reference to the effective radial length of arm 161. That is, leaving the effective radial length of arm 161 as it is, the compression imparted to the springs will be increased by shortening the effective radial length of arm 165, or it will be decreased by increasing the effective radial length of this arm 165. For instance, if the effective length of arm 165 were increased so it equalled the effective length of arm 161, no spring compression would be effected when the lever 156—161 rocked counter-clockwise. On the other hand, the shorter the effective length of arm 165 is, the greater will be the contraction of the springs, until a condition is reached such as is found in Figure 4, where the upper end of the strut 71, which corresponds to strut 163, is anchored on the stationary center 72. In this form of my invention I have found that it is preferable to make the lateral movement of the knee 164, or in other words the lineal amount that the springs 171 are compressed, somewhere between one inch and two and one-half inches because the operating efficiency of the springs in a mechanism so designed will then be approximately constant.

While I have described what seems now to be the preferred embodiment of my invention, it is conceivable that various modifications in the configuration, composition and disposition of the component elements going to make up my invention as a whole, as well as in the selective combination and application of the respective elements, may occur to those skilled in the art, and no limitation is intended by the phraseology of the foregoing description or illustrations in the accompanying drawings.

What is claimed is:

1. In a paper cutting machine, a movable clamping member, a toggle joint, one strut whereof is pivoted at a fixed point, the other strut being connected to one end of a lever of the first class, a rock-shaft carrying a rigidly attached arm, a pair of links connecting the end of said arm to the other end of said lever, an operating shaft carrying an eccentric, the strap whereof is connected to a joint whereby said links are connected, a second arm rigidly secured to said rock-shaft and operably connected to said clamping member, and a spring, one end of which is anchored to a fixed point, the other end being attached to the knee of said toggle in such a manner that the stress of the spring tends to straighten the knee.

2. In a paper cutting machine, a member adapted to descend upon a pile of paper placed in a machine to be cut, an operating member, means whereby when the operating member is operated it causes the clamping member to descend and

bear upon the paper with a resilient pressure sufficient to clamp it when it is being cut, said means comprising two toggle mechanisms the angularity of one of which decreases as the angularity of the other increases to maintain substantially constant the resilient pressure, aforesaid.

3. In a paper cutting machine, a movable clamping member, a toggle joint, one strut of which is connected to a fixed point, the other strut being connected to said clamping member, a spring, one end whereof is anchored to a fixed point, the other end being connected to the knee of the toggle joint, a shaft which moves one revolution at each cycle of the machine, means whereby during the last half of its revolution said shaft increases the bend in said knee, thereby stressing the spring, and retires the clamping member, a paper knife moved by said shaft during the first half of its cycle to cut the paper held by said clamping member, the concurrent movement of the shaft allowing the spring to operate the clamping member to clamp the paper before the knife reaches the paper.

4. In a paper cutting machine, a toggle joint, one strut whereof is connected to a fixed point, the other strut being connected to an arm rigidly secured to a rock-shaft, a spring, one end of which is anchored to a fixed point, the other end being connected to the knee of the toggle joint so its stress will tend to straighten the knee; a second arm secured to said rock-shaft, a movable clamping member and connecting means between said member and said second arm, an operating shaft which moves one revolution during each cycle of the machine, an eccentric mounted thereon, the strap whereof is connected to the first mentioned arm in such a way that during the latter half of the cycle of the operating shaft the rock-shaft is moved to crook the toggle-joint, stress the spring and retire the clamping member.

5. A paper cutting machine comprising, a knife movable through a relatively long stroke to cut stacks of paper of varying heights, a paper clamping member movable in unison with but ahead of said knife to clamp said stacks of paper, operating means for said knife and said clamping member, linkage positively connecting said operating means and said knife, linkage connecting said operating means and said clamping member, the second said linkage comprising a resilient member adapted to yield and permit said clamping member to be arrested in its stroke when it has come in contact with a stack of paper and a predetermined pressure thereon has been reached, and means including a portion of the second said linkage for diminishing the leverage through which the force of the resilient member is applied to the clamping member as the resilient member yields further during the remainder of the stroke.

6. A paper cutting machine comprising, in combination, a knife, a clamp, a knife and clamp operating shaft, eccentric means on said shaft, a knife and clamp operating member operable by said eccentric means, a toggle joint having its knee connected to said operating member, a second toggle joint, a spring having one end connected to a fixed point and the other end connected to the knee of the second toggle joint, a lever rockable midway of its ends on a fixed fulcrum, one free end of the lever being connected to a free end of the first toggle joint and the other free end of the lever being connected to a free end of the second toggle joint, a hinge connecting the other free end of the second toggle joint to

a fixed point, clamp operating linkage connected to said clamp, and means connecting the other free end of the first toggle joint to said clamp operating linkage.

5. 7. In a paper clamping mechanism for paper cutters, a paper clamp, a toggle joint one end of which is operatively connected with said clamp, a support for the opposite end of the toggle joint, a spring arranged when stressed to exert pressure 10 on the knee of the toggle and thereby to cause the clamp to grip a pile of paper, the spring being otherwise so mounted and arranged as to decrease the stress of the spring as the toggle joint straightens and to increase the stress of the 15 spring as the included angle of the toggle joint contracts.

8. In a paper clamping mechanism for paper cutters, a paper clamp, a toggle joint one end of which is operatively connected with said clamp, a 20 fixed pivot for the opposite end of the toggle joint, and a spring arranged when stressed to exert pressure on the knee of the toggle joint, the spring being otherwise so mounted and arranged as to increase the stress thereof as the included 25 angle of the toggle joint contracts.

9. In a paper clamping mechanism for paper cutters, a clamp, two levers of the first class, parallel spaced pivots for said levers, a link connecting one end of one lever to the corresponding 30 end of the other lever, a toggle joint connected at its ends to the remaining ends of the two levers, a spring connected with the knee of said toggle joint, means operatively connecting said clamp to one of said levers, and means for 35 rocking one of said levers to apply said clamp, one strut of the toggle joint being connected to its lever on a shorter radius than the other strut, said spring being so mounted and arranged as to increase the stress thereof as the included angle 40 of the toggle contracts.

10. In a paper clamping mechanism for paper cutters, a clamp, first and second toggle joints, a lever of the first class to the opposite ends of which one end of each of the said toggle joints 45 is connected, a pivotal support for the opposite end of the first toggle, the opposite end of the second toggle being operatively connected with said clamp, means for applying power to the knee of the second toggle for straightening said toggle and applying said clamp and for bending the 50 first toggle, and spring means connected with the knee of the first toggle opposing the bending thereof.

11. In a paper clamping mechanism for paper cutters, a clamp, first and second toggle joints, a lever of the first class to the opposite ends of which one end of each of the said toggle joints 55 is connected, a pivotal support for the opposite end of the first toggle, the opposite end of the second toggle being operatively connected with said clamp, means for applying power to the knee of the second toggle for straightening said toggle and applying said clamp and for bending the first toggle, spring means connected with the 60 knee of the first toggle opposing the bending thereof, and means for connecting the said pivotal support for the first toggle with the said lever of the first class to move proportionately with the movements of that lever.

70. 12. In a paper cutter having a crank shaft, a paper knife and a paper clamp arranged to stop at upper dead center of their strokes, the combination of actuating means for depressing said clamp, a spring for operating said actuating 75 means, and crank means on said crank shaft for

moving said actuating mechanism in opposition to said spring to raise said clamp, said crank means being arranged to reach dead center position when said clamp is in upper dead center position.

13. In a machine of the class described, a paper knife, a paper clamp, a toggle joint mounted at one end upon a fixed pivot and operatively connected to said paper clamp at the other end, a spring operatively connected to the knee of said toggle tending to straighten the toggle, a shaft 10 which makes one revolution for each cycle of the machine, means operatively associated with said shaft and effective during the first half of said cycle for moving said knife to effect the cutting operation, and means operatively connected with 15 the shaft and effective during the second half of its revolution for putting the spring under stress.

14. In a machine of the class described, a paper knife, a paper clamp, a toggle joint mounted at one end upon a fixed pivot and operatively connected to said paper clamp at the other end, a spring operatively connected to the knee of said toggle tending to straighten the toggle, a shaft 20 which makes one revolution for each cycle of the machine, means operatively associated with said shaft and effective during the first half of said cycle for moving said knife to effect the cutting operation, and means operatively connected with the shaft and effective during the second half of 25 its revolution for putting the spring under stress and raising the clamp.

15. In a machine of the class described, a paper knife, a paper clamp, a toggle joint mounted at one end upon a fixed pivot and operatively connected to said paper clamp at the other end, a spring operatively connected to the knee of said 30 toggle tending to straighten the toggle, a shaft which makes one revolution for each cycle of the machine, means operatively associated with said shaft and effective during the first half of 35 said cycle for moving said knife to effect the cutting operation, and means operatively connected with the shaft and effective during the second half of its revolution for putting the spring under stress and raising the clamp.

16. In a machine of the class described, a paper knife, a paper clamp, a toggle joint mounted at one end upon a fixed pivot and operatively connected at its opposite end to said paper clamp, a spring operatively connected to the knee of said 40 toggle tending to straighten the toggle, an operating mechanism, means energized by said spring and effective during the first half of the 45 cycle of the machine for moving said paper clamp into clamping position and maintaining it there during the descent of the knife, said operating mechanism also comprising means effective during the last half of the cycle for bending the 50 toggle, thereby stressing the spring, and raising the clamp to inoperative position.

17. In a paper cutting machine, a clamping member and a cutting knife operable through relatively long strokes for holding and cutting 55 stacks of paper of varying heights, a resilient means under stress urging said clamping member toward a stack of paper, means restraining said resilient means from moving said clamping means toward said stack of paper, means for 60 operating said knife, means operative ahead of said knife for releasing said restraining means thereby permitting said resilient means to move said clamping means upon said stack of paper, said resilient clamp operating means comprising 65

a toggle joint to the knee of which said spring is connected, said toggle joint constituting compensating linkage for applying substantially the same pressure to said clamping means whether 5 said resilient means is in a fully stressed or a partly stressed state.

18. In a machine of the character described, a clamping member operable through a relatively long stroke to reach and clamp stacks of paper 10 of varying heights, an operating member for moving said clamping member through its entire stroke, a spring under an initial stress interposed between said operating member and said clamping member adapted to be further stressed 15 when said clamping member encounters a stack of paper during its stroke and the operating member continues its stroke, and leverage means comprising a toggle joint between said operating member and said clamping member connected to 20 the spring at the knee of the toggle, whereby as the force of said spring increases the leverage decreases and the pressure on said stack remains substantially constant throughout the stroke.

19. In a paper cutting machine of the character described, a clamping member, a lever fulcrumed intermediate its ends on the frame of the machine and having one end connected to the clamping member, a second lever fulcrumed intermediate its ends on the frame of the machine, a toggle joint having the free end of one leg secured to the free end of the first lever and the free end of the other leg secured to one end of the second lever, operating means attached to the knee of the toggle joint to straighten the 30 legs of the joint for applying the clamping member, a second toggle joint having the free end of one leg hinged to the frame of the ma- 35

chine and the free end of the other leg secured to the other end of the second lever, and a spring under initial stress acting against the knee of the second toggle joint tending to straighten that toggle.

20. In a paper clamping mechanism of the character described, a paper clamp, a spring, an operating means, leverage means differentially connecting said operating means to said clamp and said spring, whereby the force of said operating means is divided between said clamp and said spring, said leverage means comprising a toggle to the knee of which said spring is connected and being such that when said spring gradually yields and becomes shorter and stronger, the 15 pivotal points of the levers shift gradually to cause a progressively greater proportion of the applied force of the operating means to bear on the spring and less proportion on the clamp, whereby the force applied to the clamp remains 20 substantially the same at any stage of the stress of the spring.

21. In a paper cutting machine, a knife, a movable clamping member, a toggle joint, one strut whereof is pivoted at a fixed point, the 25 other strut being connected to move said clamping member, a spring, one end of which is anchored to a fixed point, the other end being connected to the knee of the toggle joint, means effective during the down stroke of the knife 30 permitting the spring stress to straighten the knee of the toggle joint and move said clamping member to clamp a pile of paper, and means for bending the toggle and putting the spring under stress during the up stroke of the knife. 35

WALTER C. EICKMAN.
